UNITED STATES PATENT OFFICE.

VINCENT G. APPLE, OF DAYTON, OHIO.

DESIGN FOR A CASING FOR DYNAMO-ELECTRIC MACHINES.

SPECIFICATION forming part of Design No. 35,619, dated January 28, 1902.

Application filed May 20, 1901. Serial No. 61,192. Term of patent 14 years.

To all whom it may concern:

Be it known that I, VINCENT G. APPLE, of Dayton, in the county of Montgomery and State of Ohio, have invented and produced a certain new and useful Design for a Casing for Dynamo-Electric Machines; and I hereby declare that the following is a full, clear, and exact description thereof, reference being had to the accompanying drawings, which form part of this specification.

Figure 1 is a perspective view of my dynamo case or frame, showing my new design. Fig. 2 is a side elevation of the same. Fig. 3 is an end view of same.

15 In all of the views the same letters of reference indicate similar parts.

As shown in the drawings, the leading or material feature of my design consists of a truncated biconical casing A, having laterally-extending feet a on either side and projecting from the center thereof, a hinged portion a², divided by an annular bead, and a fixed portion corresponding in appearance

and of approximately the same diameter and width as the hinged portion on the opposite end of the casing, divided from the central part by an annular shoulder joining the two parts, a cylindrical projection a' concentric with the longitudinal axis of said casing, a truncated conical projection a³ concentric with the longitudinal axis of the case, a half-round vertical projection a⁴, extending laterally from the end of the case to the bottom thereof and joining the conical projection a³.

Having described my invention, what I claim as new, and desire to secure by Letters Patent of the United States, is—

The design for a casing for a dynamo-electric machine, as herein shown and described.

In testimony that I claim the foregoing as my own I affix my signature in presence of two witnesses.

VINCENT G. APPLE.

In presence of—

L. M. ARNOLD,

C. E. TAYLOR.
